Ryan M. Corbett(57) **CLAIM**

The ornamental design for a swimwear apparatus, as shown and described.

DESCRIPTION

FIG. 1 is a front view of a swimwear apparatus comprising my design;

FIG. 2 is a rear view thereof;

FIG. 3 is a right side view thereof; and,

FIG. 4 is a left side view thereof.

The broken lines shown in the drawings are included for the purpose of illustrating environmental structure and form no part of the claimed design.
